ATTORNEYS.

UNITED STATES PATENT OFFICE.

LUTHER A. HEILIG, OF SAN DIEGO, CALIFORNIA.

DESIGN FOR A PAIR OF EYEGLASSES.

55,468.

Specification for Design.

Patented June 15, 1920.

Application filed January 2, 1920. Serial No. 349,072. Term of patent 14 years.

To all whom it may concern:

Be it known that I, LUTHER A. HEILIG, a citizen of the United States, residing at San Diego, in the county of San Diego and State of California, have invented a new, original, and ornamental Design for a Pair of Eyeglasses, of which the following is a specification, reference being had to the accompanying drawing, forming a part thereof.

I claim:

The ornamental design for a pair of eyeglasses as shown.

LUTHER A. HEILIG.
